Elias Brown, of Wappingers Falls, N.Y. DES. 2085

Letters Patent No. 2085 Dated June 15, 1865.

Design for a Comb.

The schedule referred to in these Letters Patent and making part of the same.

To all whom it may concern:

Be it known that I, Elias Brown, of Wappingers Falls, in the County of Dutchess and State of New York, have invented a new and ornamental design for Combs, and I do hereby declare that the following is a full, clear and exact description thereof which will enable those skilled in the art to make and use the same, reference being had to the accompanying drawings forming part of this specification.

The drawing represents side elevations of two combs having my improvements attached.

My improved ornament is intended to be applied to all description of combs and consists in the attachment to the upper part of the comb of an ornamental bow or double loop with the upper part of the comb.

A is the comb and B the ornamental bow or double loop attached in any suitable manner to the comb, and composed of the same material of which the comb is made, or the said bow or loop may be made of any other ornamental rigid material suitable for the purpose.

When desired the comb and loop or bow may have one or more balls or other ornaments thereto attached.

Having thus described my invention I claim as new and desire to secure by Letters Patent.

The herein described design for an ornament for a comb consisting of the bow or double loop combined with the comb substantially as above and described.

The above specification of my design signed by me this 30th day of March, 1865.
